UNITED STATES PATENT OFFICE.

HERBERT E. HOLMES, OF WEST SPRINGFIELD, AND CHARLES F. GROSVENOR,
OF LUDLOW, MASSACHUSETTS.

ELECTRIC SAFETY DEVICE FOR ELEVATORS.

SPECIFICATION forming part of Letters Patent No. 443,282, dated December 23, 1890.

Application filed March 26, 1890. Serial No. 345,313. (No model.)

To all whom it may concern:

Be it known that we, HERBERT E. HOLMES and CHARLES F. GROSVENOR, citizens of the United States, respectively residing at West 5 Springfield and Ludlow, in the county of Hampden and State of Massachusetts, have invented new and useful Improvements in Electrical Safety Devices for Elevators, of which the following is a specification.

10 This invention relates to electrical safety devices for elevators.

The object of the invention is to provide means, in combination with the elevator and the elevator-well or hoistway, operative to stop the elevator on the occasion of the projection of any object or article on the car or platform across and beyond the floor through which the hoistway passes or the projection of any object on one of the floors into the hoistway. For instance, assuming that the elevator is equipped with the safety appliances and a person is riding up on the elevator-platform with his foot or arm extending across the edge of the platform, as the elevator approaches the next floor above the extended foot or arm coming in contact with a part of the safety appliance will insure the stoppage of the elevator before the platform can reach the floor to injure the person; and, furthermore, assuming

30 that a person is on a floor leaning over into and looking down the elevator-well, and the elevator should be moving down toward him, a part of the safety appliance on the moving elevator-platform will strike upon the head 35 of the endangered person, resulting in the almost instantaneous stoppage of the elevator; and to the end of providing safety appliances for elevators having the capabilities, substantially as above indicated, the invention consists in the construction and combination of 40 parts, all substantially as will hereinafter more fully appear, and be set forth in the claims.

Reference is to be had to the accompanying 45 drawings, forming part of this specification, in which the invention is illustrated.

Figure 1 is a perspective and sectional view of a hoistway and elevator. Figs. 2 and 3 are 50 enlarged illustrations of circuit-closing devices employed in the safety appliances, to be hereinafter referred to.

In the drawings, A represents a hoistway, and B the elevator, which is shown as suspended by the rope which passes over the supporting and guiding sheave to and around 55 the drum d at the top of the hoistway. There is also shown in Fig. 1 driving mechanism for the drum and power-shipping devices, which are common in elevators, and, as usual, are controlled by the power-shipping rod or 60 medium g, which extends from the top to the bottom of the building, as usual, in proximity to the hoistway.

w and x represent metallic contact-pieces supported in proximity to each other under 65 each floor, near the hoistway opening therein, said contact-pieces being insulated the one from the other, and the said contact-piece w is extended by the spring-finger 9 thereof to lie under the contact-piece x, more or less, 70 in the manner shown in Fig. 2. Binding-posts 10 and 12 are provided, one for each of said contact-pieces, to which the electric wires 14 and 15 are respectively connected, one of said wires thence running to one pole 75 of an electro-magnet 16, the other wire running from its binding-post to the battery and thence to the other pole of the electro-magnet.

D represents a movable part—such, for instance, as a bar or board, as shown in Fig. 1—ranging parallel with and in proximity to the edge of the floor, which is at one side of the hoistway, said bar D being suitably supported and guided in ways of the hangers f f for 80 an upward movement; but such bar is, under its gravity, normally maintained in its lowermost disposition shown in Fig. 1. Said vertically-movable bar is provided with the laterally-extended stud i, which normally rests 85 upon and depresses the finger-piece 9 of the contact-piece w, so that such finger is moved out of bearing upon the contact x, and whereby the circuit is continued open. Of course, as will be apparent, as the elevator ascends 90 any article or part of a person thereon which projects across the plane of said bar D will, on the abutment thereof against said bar, raise the latter, the stud i moving upwardly, permitting the upward spring of the finger 9 to close the electrical circuit, and at such 95 time the armature 18 will be drawn upwardly,

effecting a movement of the shipper-rod to stop the elevator through mechanism to be now described.

19 represents a swinging lever suitably pivotally mounted on a supporting plate or standard 20, and said lever 19 has a pin-and-slot connection with a disk 22 or other suitably-formed part, which is also mounted by a pintle 23 on said plate 20. Said disk 22 is provided 10 with the catch-notch 24 in its periphery, with which the hooked end of an angular lever 25 engages. Said angular lever 25 is pivotally supported at its elbow, and its arm 26 is extended to intersect the circular line of movement of a hammer 27, which is radially carried on a pivotally-mounted disk or part 28. Said part 28 has a notch 29 at its upper portion, with which engages a sharp projection 30 of the armature 18. It is assumed that a downward 15 movement of the shipper-rod *g* is required to start the elevator and of course an upward movement to stop it, and *j* represents a dog on said shipper-lever at the portion thereof which is in proximity to the last-described 20 electrically-actuated devices. The normal relations and dispositions of said parts to be always maintained when the circuit is open are as shown in the drawings—that is, the notch 24 of the disk 22 is about in a line horizontally extended from its center of rotation and there confined by the detent or angular lever 25. The lever 19 is so swung that its arm 32 is in its most depressed position, its other arm or extremity 33 being correspondingly upwardly inclined, and the spring 34, which, as shown, is so applied to said lever as to exert its reaction thereon to swing the arm 32 thereof upwardly. The armature, which is swung away from the electro-magnet by the 25 projection 30 thereof engaging in the notch 29 in the part carrying the hammer 27, maintains the hammer in the uplifted position. The dog *j* on the shipper-rod *g* is so adjusted that the downward movement of the shipper-rod will place the dog not quite, though almost, into contact with the arm 32 of the lever 19. In the upward travel of the elevator, should any circumstance, as hereinabove explained, effect the closing of the circuit, the 30 movement of the armature permits the dropping of the hammer, which in turn swings the angular lever or detent out of its engagement with the disk 22, when the spring 34 may effect the swinging of the lever 19 and the lifting of the shipper-rod to stop the elevator, which stoppage is practically instantaneous, and it will be clearly understood that an article, even upon and projecting beyond the platform of the elevator, on striking the 35 bar *D* will effect the stoppage of the elevator before the platform has passed from the level of the lower edge of said bar to the level of the bottom of the floor from which said bar is supported or suspended.

60 The safety devices employed for guarding against injury to persons who may be on the floor near the hoistway and looking down the

latter as the elevator descends from above are illustrated in Figs. 1 and 3, and, as shown, consist in insulated contact-pieces 37 and 38, supported on the bottom of the elevator-platform, and the contact-piece 37, having a spring-finger 39, the normal recoil of which being sufficient to carry it to bear upon the contact-piece 38, and to close a circuit formed by the wires 40 and 42, in which circuit is the electro-magnet 36 and the battery 43.

44 represents a vertically-movable part—such, for instance, as the bail shown in the drawings—which by its terminals is pivotally supported from the bottom of the elevator-platform in an oblique or downwardly inclining position, so that the cross-bar *c* lies about under the edge of the platform next to the floor. This bail is held against swinging down into a vertical plane by the hooked support 45. The armature 18' for the electro-magnet 36 actuates devices between such electro-magnet and a dog *l* on the shipper-rod *g* for moving said dog downwardly, which devices are substantially like those already described as being controlled by the electro-magnet 16, with the exception that the lever 19' is spring-constrained to act downwardly on the dog *l* instead of upwardly thereon, as 95 does the lever 19 act upon the dog *j*, and said devices intermediate of the armature 18' and lever 19' comprise the disk 22', to which the lever is connected by pin and slot, the angular detent-lever 25', and the hammer 27', carried upon the part 28', with which the armature has a detent engagement. Assuming that the shipper-rod *g* has to be thrown to its uppermost limit of movement to secure the downward travel of the elevator and that the dog *l* thereon, which, when the dog *j* is in proximity to the arm of lever 19, is removed from and is below its respective lever 19', as seen in the full lines in Fig. 1, is in its uppermost position and in proximity to and under the lever 19', as indicated by the dotted lines, also indicated by *l* in Fig. 1, the movable part or bail 44 being then from any cause, as hereinbefore suggested, raised as the elevator descends, (as by such bail striking the head, arm, or foot of a person on the floor, which part may be projected into the hoistway,) the finger 39 may spring to contact with the contact-plate 38, closing the circuit and insuring the downward swinging of the lever 19' and the downward movement of the shipper-rod to immediately stop the elevator. The electric wires 40 42, which by their one ends move with the elevator, are necessarily arranged in a loop form, as at *m*.

What we claim as our invention is—

1. The combination, with the contact-pieces *w* and *x*, suitably supported on the floor adjacent the hoistway, the one *w* having the spring-finger *g*, the horizontal bar or part vertically movable and supported from the floor adjacent its edge at the hoistway and provided with a stud *i*, of a power-shipping rod provided thereon with a dog, an electro-mag-

net, and wires running therefrom to each of said contact-pieces, and one of said wires comprising an electric generator, and a lever 19, mounted to swing and to move said shipper-dog and having an operative connection with said electro-magnet, substantially as described.

2. The combination, with suitable supports adjacent to the hoistway, of two contact-pieces, one having a finger normally adapted to bear upon the other, and a vertically-movable part suitably supported, guided, and located along near the hoistway and normally adapted to force the spring-finger of the one contact-piece away from the other, an electro-magnet and wires running therefrom to each of said contact-pieces, one comprising an electric generator of the power-controlling me-

dium for the elevator, a swinging lever 19, located for an engagement with said power-controlling medium and having the spring 34 applied thereto, the pivoted disk or part 22, provided with the catch-notch 24, and to which said lever 19 has a pin-and-slot connection, the angular detent-lever 25, the hammer 27 and its notched carrying part 28, and the projection 30 of the armature of said electro-magnet, adapted to engage the notch in said hammer-carrying part, substantially as and for the purpose set forth.
